UNITED STATES PATENT OFFICE.

JOHN STRAKA, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed April 28, 1922, Serial No. 557,199. Renewed November 10, 1924.

My invention relates to pencils, and particularly to that class known as mechanical pencils.

The primary object of the invention is to provide a structure that is simple and economical to manufacture, it having very few parts, and those parts being easily constructed and exceedingly durable. A further object of my invention is to provide a simple mechanism for repelling and propelling the lead into and from the tip by a relative co-acting movement of the tip and the barrel. A still further object of my invention is to provide the aforementioned propelling mechanism with means for excluding all of the lead from the tip.

Other objects will appear hereinafter as the specification proceeds.

The invention consists in the combinations and arrangements of parts hereinafter described and claimed and will be best understood by reference to the accompanying drawings forming a part of this specification, and in which,

Fig. 1 is a side elevation view of the mechanical pencil disclosed in my specification,

Fig. 2 is a longitudinal sectional view,

Fig. 3 is a sectional view of part of the propelling mechanism,

Fig. 4 is a side elevation of the rotatable and removable tip,

Fig. 5 is a cross sectional view on the line 5—5 of Fig. 2, and

Fig. 6 is a cross sectional view on the line 6—6 of Fig. 2.

The numeral 1 indicates a barrel milled at its lower extremity to form a flush seat for a rotatable tip 2, and milled at its uppermost extremity to form a flush seat for a sleeve 3 wherein is seated an eraser 4 in the manner as shown in the drawing. Inferiorly of the barrel are apertures 5 and 6, the upper being used for the holding of surplus leads, the lower being fashioned to permit the entrance of a feeding mechanism 7 and an extended portion 8 of the tip 2. The uppermost portion of the aperture 6 is reduced and squared to permit longitudinal movement of the squared end of the feeding mechanism 7 and its co-operating part 9, but being so formed as to prevent relative turning of the aforementioned parts, the lower portion of the aperture being circular in conformation to permit the turning of the squared ends of the members 7 and 9

when they have advanced from the squared aperture into the circular aperture.

Fixedly mounted in the tip portion and extending upwardly therefrom is a shell 8 having rolled threads 11 thereon at its uppermost portion. The shell 8 is fixed in the tip through the medium of soldering or as shown in the specification. A small washer 10 which is fixed to the shell and tip cooperates with the reduced portion of the tip 68 to hold said shell fixedly in said tip.

The portion of the lead propelling mechanism indicated by the numeral 7 is formed of a hollow shell swedged and slotted at one end to form a clutch for gripping the lead 70 and having threads rolled thereon to cooperate with the threads in the member 8 for advancing and retracting said mechanism to and from the tip. The upper portion of the member 7 is squared as at 14, and as explained heretofore, is so formed to prevent relative turning between the member 7 and the barrel 1 until the feeding mechanism has advanced into the aperture 6. Mounted in the hollow member 7 is a projecting wire 9 its lower portion 9^a being indented as at 15, said indentation being formed to act as threads which co-operate with the internal threads of the member 7 for advancing the projecting wire 9^a longitudinally of the said member 7. Fixed on the uppermost portion of the projecting wire 9^a is a squared head 12. To prevent the projecting wire 9^a from becoming completely disengaged from the member 7, the said member 7 is indented as at 13, said indentation being placed between the threads as illustrated in Fig. 3.

The operation of the pencil is as follows:

When the lead has been exhausted from the tip, the tip is pulled longitudinally away from the body, said separation bringing with it members 8, 7 and 9. The projecting wire 9^a is then unscrewed until the thread thereon contacts with the stop 13. A lead is introduced into the slotted end of the member 7 until it contacts with the end of the projecting member 9^a. The member 7 is then screwed into the threaded tube 8 and the square heads of the member 7 and 12 are aligned; whereupon the whole mechanism is slipped into the lower aperture and turned until the heads 12 and 14 will engage in the squared portion of the aperture 6. The flanged portions of the tip will slip over the 110

milled end of the barrel and the mechanism is frictionally held therein by said engagement. To propel the lead the tip is held firmly in one hand and the barrel is turned 5 in a clockwise direction. The squared heads 12 and 14 will prevent the feeding mechanism from turning relatively to the barrel until said feeding mechanism has traveled a limited distance; the threads on the feeding 10 mechanism co-operating with the threads of the member 8 fixed to the tip 2 cause the feeding mechanism to be advanced longitudinally and the lead thus propelled. This advancement of the feeding mechanism 15 will continue until the squared head 14 reaches the circular shaped portion of the aperture, whereupon the member 7 will revolve with the tip 2. The projecting wire 9^a and the squared head 12 continue to advance until the said head 12 will clear the squared aperture and enter into the circular shaped aperture. This will result in the forcing of the remaining particle of lead 20 from the clutch at the end of the member 7, leaving the said clutch clear and ready for the reception of another lead.

While I have illustrated and described the preferred form of construction for carrying my invention into effect, this is capable of 30 variation and modification without departing from the spirit of the invention. I, therefore, do not wish to be limited to the precise details of construction set forth, but desire to avail myself of such variations and 35 modifications as come within the spirit of the invention.

Having described my invention, what I claim as new and desire to secure by Letters Patent is:—

40 1. A pencil comprising a hollow handle portion having a lengthwise extending open ended guideway therein, a pencil tip rotatably and removably secured on the open end of said handle portion, a lead receiving 45 tubular member removable with said tip and extending into said handle portion and formed with a spiral track, a lead feeding member relatively movable in said tubular member and having track engaging means 50 co-operating with said spiral track to move the lead feeding member in an endwise direction when said tubular member is rotated relative to said lead feeding member, means 55 for holding a lead in said lead feeding member and means for expelling said lead therefrom when the lead feeding member has progressed to the lower extremity of the tip.

60 2. A pencil comprising a barrel, a tip rotatably and removably engaging said barrel, a lead support provided with externally and internally threaded portions, a sleeve member secured at one end to said tip and having a portion complementary to the external 65 thread of said lead support, a fragment

ejector having a portion complementary to the internal thread of said lead support, means for preventing relative rotation of said barrel and said lead support, so that relative rotation of the barrel and the tip 70 will cause said lead support to travel longitudinally of the barrel, said rotation preventing means being active until the lead support has travelled a predetermined distance, and means for preventing relative rotation of said lead support and said fragment ejector, so that when the lead support is freed from its rotation preventing means 75 a relative rotation of said lead support and said fragment ejector may be obtained. 80

3. A pencil comprising a barrel, a tip rotatably and removably engaging said barrel, a lead support longitudinally movable within said barrel and having a helical guide, a sleeve member secured to said tip and having means engaging said helical guide, said barrel and said lead support having automatically releasable means for preventing relative rotation thereof, so that said sleeve 85 will cause said lead support to travel longitudinally in said barrel when the barrel and the tip are rotated relative to each other, a lead fragment ejector having means actuated by said helical guide, and means preventing relative rotation of said barrel and said fragment ejector, so that when the lead support 90 is freed from its rotation preventing means, a relative rotation of said lead support and said fragment ejector may be obtained. 95

4. A pencil comprising a barrel, a tip rotatably and removably engaging said barrel, a lead support, a sleeve fixed to said tip, said sleeve and said lead support having complementary means by which relative rotational movement will effect longitudinal travel of said lead support; means for preventing relative rotative movement of said barrel and said lead support during the longitudinal travel 105 of the lead support comprising a non-circular portion on said support slidable in a non-circular opening in said barrel, so that relative rotation of the barrel and the tip will produce said longitudinal movement, a lead 110 ejector engaging said lead support, and means operated by relative rotation of the barrel and the tip for advancing said ejector 115 at the end of the longitudinal movement of said lead support.

5. A pencil comprising a barrel having a 120 bore formed with a non-circular portion and an enlarged portion; a tip rotatably and removably engaging said barrel, a lead support having a non-circular head adapted to 125 slide in the non-circular portion of the barrel bore, means operated by relative rotation of said barrel and said tip for imparting longitudinal movement to said lead support, a lead ejector engaging said lead support and 130 having a non-circular head, and means op-

erated by relative rotation of said barrel and said tip for advancing said lead ejector at the end of longitudinal movement of said lead support in one direction.

- 5 6. A pencil comprising a barrel, a tip rotatably and removably engaging said barrel, a lead support having a non-circular head, screw threaded engagement means operated by the relative rotation of said barrel and 10 said tip for imparting longitudinal movement to said lead support, a lead ejector engaging said lead support and having a non-circular head, and means cooperating with said threaded engagement means and said 15 non-circular heads and operated by relative rotation of said barrel and said tip for advancing said lead ejector at the end of the longitudinal movement of the lead support in one direction.
- 20 7. A pencil comprising a barrel having a bore of circular cross-section leading in from one end and provided with an extension of reduced angular cross-section, a tip rotatably and removably engaging said barrel, a lead 25 support longitudinally movable in said bore and having a portion complementary to and engaging the angular extension of the bore to prevent relative rotation, means operated by relative rotation of said barrel and said tip for imparting longitudinal movement to 30 said lead support until said support is disengaged from the extension of said bore, a lead ejector having a portion complementary to and engaging the angular extension of said bore to prevent relative rotation of the 35 ejector and the barrel, said ejector and said lead support having complementary means for advancing the ejector upon continued relative rotation of the barrel and the tip after 40 said lead support has been moved out of engagement with the angular portion of said bore.
8. In a pencil a hollow handle having a longitudinal guideway therein, a tip rotatably and removably mounted on one end of 45 said handle, a lead support associated with said tip and handle, a lead fragment ejector

mounted in said guideway and associated with said lead support and said handle, said lead support being also mounted in said 50 guideway, against rotation with relation to the handle but movable longitudinally therein until it moves out of said guideway after which the handle and support rotate relatively to each other while the ejector continues to advance in said guideway to eject the unused fragment of lead.

9. In a pencil a hollow handle having a tip rotatably mounted thereon, a lead support associated with said tip and handle, and a 60 lead fragment ejector, said ejector and support being fixed to rotate together for a part of their travel and arranged to thereafter rotate relatively to each other continuously through a substantial distance for ejection 65 of the unused fragment of lead.

10. In a pencil a hollow handle having a tip rotatably mounted at one end, the hollow of the handle being non-circular in cross-section for a portion of its length, and circular for another portion of its length, a lead support associated with the tip and handle, a lead fragment ejector, the support and ejector each having a non-circular head adapted for longitudinal non-rotatable movement 70 in said non-circular portion of the handle opening, the head on the support having rotational movement in the circular portion of the handle as soon as it has longitudinally passed out of the non-circular portion. 75

11. In a pencil a hollow handle, a tip, a lead support and a lead fragment ejector, and means for causing the support and ejector to be fixed against rotation relatively to each other but move longitudinally together in 80 the handle and to thereafter rotate relatively to each other through at least substantially a complete revolution upon reaching a predetermined point to eject the unused fragment of lead.

In testimony whereof I have signed my name to this specification.

JOHN STRAKA.
